UNITED STATES PATENT OFFICE

JAMES R. COLE, OF TULSA, OKLAHOMA

POWER UNIT

Application filed November 11, 1927. Serial No. 232,679.

This invention relates to improvements in oil well pumping apparatus, and has for its object to provide an equipment whereby an ordinary standard rig may be employed to pump a plurality of wells.

A further object of my invention is to provide an oil well pumping power wherein the band wheel shaft, or equivalent shaft, is horizontal, and which in itself is a complete power unit, simple in operation and construction, capable of having a balanced stroke with an equal distribution of the strain, and adapted to pump more and deeper wells than is now possible with such rigs.

15 A still further object of my invention is to provide apparatus of the above type, comparatively inexpensive, conveniently and quickly set up and taken down, cheap in operation and upkeep, and one which has a very 20 high salvage value.

With the above and other objects in view which will appear as the description proceeds, my invention consists in the novel features hereinafter set forth in detail, illustrated in the accompanying drawings, and more particularly pointed out in the appended claims.

Referring to the drawings, in which numerals of like character designate similar 30 parts throughout the several views,

Fig. 1 is a view of the apparatus in side elevation, showing a complete eight well connection power in which the pitman is used to pump the well at which the power is located, said pitman operating the walking beam in the usual manner.

Fig. 2 is a top plan view of the apparatus, showing the relative positions of the band wheel and deflectors.

40 Fig. 3 is an enlarged perspective view of one of the swivelled deflectors.

Fig. 4 is a similar view of one of the rigid deflectors.

Fig. 5 is a side view of a modified form of 45 wrist pin iron, or wrist pin connecting plate.

Fig. 6 is a top view of the same, and

Fig. 7 is a modified form of deflector swivel or connection.

In the drawings, 1 represents the main sill 50 of the rig resting on a plurality of mud sills

2 and supporting the conventional Sampson post 5, extending upwardly therefrom and braced in the usual manner. 3 represents the rear jack post sill resting on the mud sills. 4 represents an additional sill upon which deflectors may be fastened and which is bolted to the mud sills and to the rear jack post sill. 55 6 represents the conventional walking beam pivotally mounted on top of the Sampson post 5 by means of the usual center irons 7. 60

Rotatably mounted on the sills 1 and 3, in suitable bearings on the conventional jack posts 9, is a band wheel 8 which may be driven from any source of power, not shown. From either end of the shaft 10 which supports the 65 band wheel 8 to which it is attached, I secure crank levers 11 and 12 set opposing each other and each having outwardly projecting wrist pins 13 at their free ends. Swivelled on the wrist pins 13, I provide vertically extending connecting plates or wrist pin irons 14 and 14' provided along their edges with a plurality of apertures 15 adapted to receive 70 connections on the sprocket chain, pitman 75 and rods, as hereinafter set forth.

16 designates a rigid deflector mounted on the sill 4 at a point thereon where the pull on the sprocket chain run to this deflector will be approximately forty-five degrees off the plane of the plumb line of the axis of the band wheel shaft 10, when the pull on the chain is on center. This style of deflector comprises a base portion 17 adapted to be secured to the sill to which it is attached and having angularly disposed upwardly extending integral projections or arms 18, the upper 80 ends of which are apertured to receive the shaft of the sprocket wheel 19 which is rotatably mounted therein, as shown in Fig. 4. The sprocket wheel 19 of the rigid deflector 85 16 is mounted in line with the movement of the wrist pin on the crank 12.

On the same sill 4, and on the opposite side of the crank, located in the same relative position to said crank as is the rigid deflector 90 mentioned, I secure a swivelled deflector 20, while on the main sill 1, on the opposite side of the rig, and extending in a line at right angles to the axis of the band wheel shaft 10, I mount two swivelled deflectors 21 and 22, 100

one on either side of said shaft, and each being located so that the pull on the sprocket chain passing through them will be approximately forty five degrees off the plane of the 5 plumb line of the axis of the shaft when the pull on the chain is on center. Another swivelled deflector 23 is attached to the main sill 1 in the plane of the plumb line of the axis of the shaft 10. Each of the swivelled deflec- 10 tors comprises a base member 24, adapted to be secured firmly to the sills whereon they are located, and having swivelled thereto, on a shaft 24', an angularly disposed upwardly extending sprocket wheel frame 25, in 15 which is rotatably mounted a sprocket wheel 26, see Fig. 3. If desired, these deflectors both rigid and swivelled, may be provided with a casing or guard 27, as clearly shown in the drawings in Fig. 3 and Fig. 4.

20 In Fig. 7, I have shown a modified form of swivelled deflector, comprising a base 36 having an upwardly projecting, laterally disposed ring 37 on the upper surface thereof, and a sprocket wheel yoke 38 provided with 25 a hook member 39 at its lower extremity, and adapted to be hooked into said ring 37, whereby freedom of movement in any direction is afforded when power is applied to the chain running over the sprocket wheel 30 mounted in said yoke. However, the form of deflector shown in Figs. 3 and 4 is preferable to the one shown in Fig. 7 as with the deflector swivelled on a journal it can swivel 35 only in a fixed plane and the tangent of pull from deflector to pitman head will remain substantially in the plane generated by the movement of the pitman head.

Secured by connections in the proper ap- 40 tures, as shown at 15, in the wrist pin irons or plates 14 and 14', on the wrist pins of the cranks 11 and 12, is a plurality of chains which engage and run on the sprocket wheels as follows. The chain 28 runs from 14' to the rigid deflector 16, while the chain 29 runs to 45 the swivelled deflector 20, and the chains 30, 31 and 32 run from plate 14 to the swivelled deflectors 21, 22 and 23 respectively, as clearly shown in Figs. 1 and 2 of the drawings.

The chains are connected at their other 50 ends by means of suitable connections, to rod lines running to the pumping jacks at the wells to be pumped through the use of these deflectors, and the rod lines are disconnected 55 from the power by the conventional hook off or knock off.

33 and 34 designate rod lines to pumping jacks directly connected to plate 14' swivelled on the wrist pin of crank 12, the connec- 60 tion being made in apertures as at 15, which said rod lines pull in a horizontal direction, and are capable of being disconnected in the usual manner. 35 represents the pitman connection between the walking beam 6 and the 65 crank 11, and comprises a rod connected in an

aperture such as shown at 15, in plate 14 on the wrist pin on said crank.

It is obvious that instead of the pitman rod, such as shown in the drawings, being used, the regular pitman such as is used on a stand- 70 ard rig may be employed, in which event the chains 30, 31 and 32 could be directly connected to the pitman itself.

It is also evident that instead of using 75 cranks and wrist pins as shown, conventional eccentrics on the band wheel shaft could be employed to impart the reciprocating motion to the pitman or pitman rod 35, rods 33 and 34, and the chain mentioned.

It is further apparent that the rigid and 80 swivelled deflectors may, in certain instances, be used interchangeably, the use of the par- ticular kind at any particular place being governed by individual conditions. Fur- 85

thermore, that the deflectors need not be mounted on or attached to any of the sills mentioned, but may be secured to a foundation or mount- 90 ed in any other manner suitable to stand the strain. Moreover, it is obvious that while

the use of a sprocket wheel and sprocket chain 95 has some advantage over other means to de- deflect the pull on the wrist pin, so that it may come at the required angle with reference to the line of pull on the other rods, chain or pitman, to give an equal distribution of

power impulses or strains throughout the 100 revolution of the band wheel, yet means other than a sprocket wheel and chain could be em- ployed. Cable or wire line could be used in a pulley or sheave. A segment of a circle in- 105 stead of a wheel could be employed, and even a lever or two used to deflect the pull on the rod line, could be used.

Furthermore, it is obvious that if it is not 110 desired to pump the well at which the rig power is located, through the use of the pit- man and walking beam 6, that the pitman may be dispensed with, and the well put on a

jack with the rod line run through a deflector located on the main sill and forward of the band wheel shaft. In this even, to make up 115 for the loss of the pitman connection, and in its place and to balance the power as be- fore, another deflector is located in the plane

of the plumb line of the axis of the band 120 wheel shaft and between the deflectors 16 and 20, and connection made to the wrist pin iron or plate on the wrist pin on crank 12, and a rod line run from this. As the pull on the shaft is vertical, the same as the pull by the pitman, and as the two cranks are opposed, the substitution is perfect.

The operation of my invention is as fol- 125 lows:

The band wheel 8 is set into operation, ro- 125 tating in the direction of the arrow, Fig. 1, causing the shaft 10 to rotate in its bearings, which in turn revolves the crank levers 11 and 12 around the axis of said shaft. This causes the swivelled plates 14 and 14' mount- 130

ed on each of said crank levers, eccentric with respect to the said band wheel 8, to rotate and impart an oscillating motion to the pitman 35, the rods 33 and 34, and the chains 5 28, 29, 30, 31 and 32, connected to said plates 14 and 14'. The chains are connected to rod lines and run over the deflectors which permits the strain to come at the desired angle with reference to the band wheel shaft, so 10 that the power is balanced. It will be noted that the chain 28 oscillates in a line with the rotation of the said crank 12, moving in the plane of the movement of the wrist pin on said crank, and therefore the deflector 16 may 15 be rigid, but as the remainder of the chains are directed to wells at different angles to the rotation of the cranks and band wheels aforesaid, it is necessary to employ swivelled deflectors which automatically become in 20 alignment on their swivels as power is applied to the unit. It is not necessary that the swivelled deflectors be set at right angles to the plane of the wrist pin movement, as is shown in the drawings, although with this 25 setting the alignment is perfect, but if the deflectors are set at any angle, the play out of line is not great enough to render the setting impractical.

It will be seen that I have provided an 20 eight well connection balanced power unit, which may be built as a unit or with the means of which a standard rig may be converted into a power as shown. This invention permits the revolution of the band wheel 25 or band wheel shaft, to be divided into as many equal parts as there are well connections to be made to the power, so that each well will be picked up in sequence in equally divided power impulses or strains. Also 30 each well in this instance as in all cases where an even number of well connections are made, is balanced with another well, at all times, as connection 35 offsets connection 32, 33 offsets 34, 28 balances with 30 and 29 with 35 31.

My invention however is not limited to an 30 eight well connection power, as from two to eight well connections may be had with substantially the same results by using one or more deflectors properly positioned with relation one to the other and to the cranks, employing the deflectors either with or without the pitman, as will be illustrated. There are 40 hundreds of combinations available, but only one for each number of well connections will be mentioned, in the following arrangements:

For two wells: Use the regular standard 50 pitman in the usual way to pump on the beam. Set the deflector on the main sill in the plane of the plumb line of the axis of the band wheel shaft. Connect the chain used with this deflector, to the pitman direct, and pump the second well through the deflector. 55 The two wells balance and each is picked up

in sequence at one half revolution of the band wheel. This is, particularly on deep wells, an advantage over connecting the second well to a rod line that operates in a horizontal direction, as with the use of the deflector the 70 strain is vertical and the rig is not pulled to pieces. If the second well to be pumped is on the other side of the rig, the crank 12 is used, in which instance the two cranks 11 operating the pitman, and 12 the deflector, 75 must be set parallel to each other, that is, in the same direction, instead of being opposed to each other as shown in the drawings for an eight well connection power.

For a three well connection: Use the regular 80 pitman and two deflectors placed at approximately 60 degrees off the plumb line of the shaft, locating both on one side of the rig or one on each side, depending upon the direction in which the rod lines run to the two 85 additional wells to be pumped. Each well is picked up in sequence, at one-third revolution of the band wheel. If the crank 12 is employed, as would necessarily be the case 90 if one or both of the deflectors were placed on that side of the rig, the two cranks must be set parallel and not opposed to each other.

For four well connection: Use the conventional standard pitman to pump the original well on the beam in the usual manner. 95 Place the crank 12 in line with the pitman crank 11, and not opposed to it as it appears in the drawings, locate one deflector under the crank 12 in the plane of the plumb line 100 of the axis of the band wheel shaft, by attaching it to the mud sill under the jack post, and operate one well through this deflector. Connect the remaining two wells to rod lines as shown at 33 and 34. Each well is picked up 105 in sequence at one-fourth revolution of the band wheel. The two wells on rod lines 33 and 34 counter-balance each other, and the pitman well and the deflector well likewise counter-balance each other.

Five well connection: Use the regular pitman and four deflectors properly positioned two on each side of the rig so that the revolution of the band wheel will be divided into five equal parts, and each well picked up on one-fifth of the revolution. The two cranks should be set opposed to each other, as is shown in the drawing of an eight well connection power.

Six well connection: Either use the regular pitman and five deflectors, two on one side and three on the other, properly spaced so as to divide the band wheel revolution into six equal parts where each well will be picked up on one-sixth revolution and with the two cranks set opposed to each other; or set the cranks opposed to each other, eliminate the pitman, and set three deflectors on one side and three on the other, and pump the well which ordinarily would be pumped on the beam through the pitman connection, with 125 130

a jack operated through the deflector located on the main sill 1 in front of the crank 11, the deflectors being so spaced that the wells are picked up in sequence of one-sixth revolution of the band wheel.

5 Seven well connection: Use the same arrangement as for the eight well connection shown in the drawing, and use the conventional stone boat or dummy in place of the eighth well, so that all wells will be counterbalanced.

10 Eight well connection: The same as shown in the drawings.

15 It will be noted that I have provided a portable apparatus, easily moved from one place to another, and requiring no expensive foundation as in powers heretofore known. My apparatus may be used with equal effect for pumping several wells on a drilling machine, or on any rig or machine having the shaft in horizontal position. It need hardly be mentioned that with the deflectors and wrist pin irons shown, and the necessary connections, the ordinary standard rig can be 20 quickly converted into a balanced power unit.

25 From the foregoing, it is believed that my invention may be readily understood by those skilled in the art without further description, it being borne in mind that changes may be 30 made in the details disclosed without departing from the spirit of the invention as expressed in the claims.

35 What I claim and desire to secure by Letters Patent is:

40 1. A power unit comprising a base member, a vertically extending post secured thereto and having a rocker arm mounted on the top thereof, a power driven band wheel on said base member, a horizontal shaft supporting said wheel and rotatable therewith, a crank lever fixed on each end of said shaft and provided with a wrist pin at its free end, a vertical connecting plate rotatable on each of said wrist pins, pull deflectors, 45 comprising sprocket wheels, mounted on said base on either side of said band wheel, and sprocket chains connected to said plates on the wrist pins, and engaging said deflector sprocket wheels, from whence they run to a plurality of well pumps located at different 50 points around said unit, and with a pitman connecting one of said plates with said rocker-arm.

55 2. A power unit for pumping oil wells, consisting of a rotatably mounted substantially horizontal shaft and means of rotating the same; a gyratory member on said shaft and actuated thereby; a flexible power element connected with said gyratory member 60 and adapted to also be connected to a rod line to pump a well; and means located at said power unit and positioned below the horizon of said shaft and adapted to change the direction of the movement of said flexible power element from any of its radial posi-

tions relative to said gyratory member, to a substantially straight line position within the plane generated by the motion of the gyratory member.

3. A power unit for pumping oil wells, 70 consisting of a rotatably mounted substantially horizontal shaft and means of rotating the same; a gyratory member on said shaft and actuated thereby; a flexible power element connected with said gyratory member and adapted to also be connected to a rod line to pump a well; and means located at said power unit and positioned below the horizon of said shaft and adapted to change the direction of the movement of said flexible power element from any of its radial positions relative to said gyratory member, to a substantially straight line position which is 75 outside of the plane generated by the motion of the gyratory member.

4. A power unit for pumping oil wells, 80 consisting of a rotatably mounted substantially horizontal shaft and means of rotating the same; a gyratory member on said shaft and actuated thereby; a plurality of power transmitting elements attached to said gyratory member, one of which said elements is flexible; and a deflecting means located at said power unit and positioned below the horizon of 85 said shaft and adapted to be cooperatively associated with said flexible power transmitting element whereby its motion is deflected from any of its radial positions relative to said gyratory member, at an angle within the plane generated by the motion of said gyratory member.

5. A power unit for pumping oil wells, 90 consisting of a rotatably mounted substantially horizontal shaft and means of rotating the same; a gyratory member on said shaft and actuated thereby; a plurality of power transmitting elements attached to said gyratory member, one of which said elements is flexible; and a deflecting means located at said power unit and positioned below the horizon of 95 said shaft and adapted to be cooperatively associated with said flexible power transmitting element whereby its motion is deflected from any of its radial positions relative to said gyratory member, at an angle within the plane generated by the motion of said gyratory member.

6. A power deflector thru which a rod line 100 may be operated to pump an oil well by a power unit of the type hereinafter set forth, with said power deflector adapted to be attached to any suitable foundation and to be positioned at the base of said power unit and below the horizon of the shaft thereof, which 105 said power unit is of the style consisting of a horizontally disposed and revolvably mounted shaft and means of revolving the same, and a crank on said shaft and a wrist pin on said crank and a pitman head on said 110 wrist pin, and with means on said pitman 115 connecting one of said plates with said rocker-arm.

120

125

130

- head for connecting thereto a rod line member of the aforesaid rod line; a flexible power transmitting means provided in said power deflector adapted to be connected to said pitman head and to said rod line; and means provided in said power deflector for engaging said flexible power transmitting member and for deflecting the pull of the same downwardly from said pitman head, substantially in the plane generated by the movement of said pitman head, and means also provided in said power deflector for deflecting said downward pull of said flexible power transmitting member out of the plane generated by the movement of said pitman head. 70
7. An apparatus adapted to be attached to the ordinary standard rig used for pumping oil wells and having a horizontal shaft with band wheel thereon and a crank on one end of said shaft and a wristpin on said crank, and a walking beam mounted at the rig and a pitman connecting said walking beam with said wrist pin, and with said rig also having a crank on the other end of said shaft and a wristpin on said crank; an apparatus as aforesaid adapted to convert said standard rig into a balanced power to pump a plurality of wells by distributing the pumping strains on said wells at equal intervals throughout the course of the revolution of said shaft, said apparatus consisting of a multiple pitman head adapted to be rotatably mounted on the last named wrist pin and provided with a plurality of connections for rod lines two of which connections are adapted to receive rod lines directed to said connections in a substantially horizontal plane and another of which said connections is adapted to receive a rod line directed to it from below; a flexible power element attached to said last named pitman head connection and adapted to be connected to a rod line; a power deflector adapted to be secured to any suitable foundation at the base of said standard rig and positioned below the horizon of the shaft thereof, and with said power deflector provided with means for engaging said flexible power element and adapted to change its direction of movement to a substantially horizontal position within the plane generated by the movement of said pitman head. 80
8. An apparatus as claimed in claim 7; and with said power deflector also provided with means for deflecting the movement of said flexible power element outside of the plane generated by the movement of said pitman head. 90
9. A power deflector as claimed in claim 6, and wherein said means provided in said power deflector for deflecting the pull as aforesaid, is a wheel rotatably mounted in a yoke swiveled on a base plate adapted to be attached to the aforesaid foundation; and with said wheel adapted to engage said flexible power element. 100
10. A power deflector as claimed in claim 6, and wherein said means provided in said power deflector for deflecting the pull as aforesaid, is a wheel rotatably mounted in a yoke swiveled on a journal held on a base plate adapted to be attached to the aforesaid foundation, and with said wheel adapted to engage said flexible power element. 110
- In testimony whereof I affix my signature. 120
